(57) **CLAIM**

The ornamental design for a bar for releasing and winding load straps, substantially as shown and described.

DESCRIPTION

FIG. 1 is a right side, front perspective view of a first embodiment of the bar for releasing and winding load straps showing the new design;

FIG. 2 is a bottom plan view thereof;

FIG. 3 is a top plan view thereof;

FIG. 4 is a rear elevation view thereof;

FIG. 5 is a front elevation view thereof;

FIG. 6 is a right side elevation view thereof;

FIG. 7 is a left side elevation view thereof;

FIG. 8 is an exemplary illustrative view of the bar for releasing and winding load straps winding a load strap;

FIG. 9 is an exemplary illustrative view of the bar for releasing and winding load straps releasing a load strap; and,

FIG. 10 is an exemplary illustrative view of the bar for releasing and winding load straps tightening a load strap.

The bar for releasing and winding load straps is shown with a symbolic break in its length. The appearance of any portion of the article between the break lines forms no part of the claimed design.
